UNITED STATES PATENT OFFICE.

EDMUND O. SCHWEITZER, OF CHICAGO, ILLINOIS.

OIL SWITCH.

Application filed October 9, 1922. Serial No. 593,248.

My invention relates to electric power equipment, and more specifically to circuit interrupting means particularly adapted for interrupting circuits of high voltage, or 5 large power or both, commonly referred to as an oil switch. Equipment of this sort customarily comprises a suitable receptacle filled with an insulating and to some extent arc-extinguishing and more or less combustible liquid, and mechanical contact making and breaking means immersed in said liquid. While the liquid employed is customarily oil and the switch is, therefore, referred to as 10 an oil switch, it should be borne in mind, that other liquids are available. Throughout the following specification and claims the term "oil switch" should be construed to mean the type of switch customarily filled with oil, in contradistinction to such a 15 switch filled with any particular liquid.

There are many liquids more efficient in extinguishing an electric arc than oil, but so far as I am at present aware, no such liquid has, up to the present time, been made commercially available, which did not have more or less tendency to evaporate (due to its volatile nature) unless the enclosure was sealed, which is not usually feasible in oil 20 switches; and also to attack and corrode the mechanical contact making and breaking means employed, or which would maintain its value as an insulating medium when exposed to air and moisture. On this account, the use of oil is still practically universal in switches of this type.

When a switch of this character opens under heavy current flow, the resulting arc vaporizes the surrounding medium. If that medium is oil, the resulting vapor is inflammable. It is one of the objects of the present 25 invention to provide a liquid in contact with the arc at the time that the switch opens which will evolve a vapor which is not inflammable, and which has, in fact, a fire and arc-extinguishing characteristic. To this end I normally maintain the contacts in a bath of oil for insulating purposes and maintain available for instant replacement either by movement of the liquid itself with respect 30 to the switch contacts or by movement of one or more of the switch contacts with respect to the liquid a body of liquid of suitable character to extinguish the arc and to give off a non-inflammable or arc-extinguish-

ing vapor if and when it is heated to the 55 vaporizing point by the arc.

Another object of my invention is to improve the efficiency of this type of switch, with particular reference to the features just above discussed. 60

Another object is to increase the arc-extinguishing power of such switches.

Another object is to fill the container at the time the switch opens with a substance of maximum efficiency in extinguishing the 65 arc.

Another object is to keep the container before the switch opens, with all metal or other parts liable to corrosion, immersed in a liquid of maximum efficiency in preventing 70 corrosion and high efficiency in extinguishing the arc.

Another object is to provide excess load and timing means for timing the supply of special arc-extinguishing fluid to suit the 75 time and other characteristics of the switch and of the system of which said switch forms a part.

Another object is to provide for conveniently and quickly restoring such a 80 switch to initial condition after it has opened.

Further objects and advantages of the invention will become apparent as the description proceeds. 85

In the accompanying drawings:

Figures 1 and 2 are cross-sectional views on lines 1—1 of Fig. 2 and 2—2 of Fig. 1 respectively, showing the application of the principles of my invention to one well-known type of oil switch; 90

Figures 3 and 4 are similar views, illustrating a different mode of applying my invention to the same switch;

Figures 5 and 6 are sectional views on 95 lines 5—5 of Fig. 3 and 6—6 of Fig. 5 respectively, illustrating the application of a form of my invention generally similar to that shown in Figs. 3 and 4, to a different switch; and

Figure 7 is a fragmentary section showing a modification of the structure of Fig. 5.

In the embodiment of my invention selected for illustration in Figures 1 and 2, a container 10, preferably of insulating material, is supported in a metal casing comprising side walls 12 and a bottom 14. Surmounting side walls 12 is a casing 16

containing the switch operating means (not shown). Insulators 18 project downwardly from casing 16 to insulate and support contact terminals 20. A vertically slideable rod 22 carries a cross-piece 24 at its lower end, having contact elements 26 at opposite ends in alignment with terminals 20. It will be apparent that vertical movement of rod 22 operates to move the cross-piece 24 into and out of operative position to connect and disconnect terminals 20.

The switch parts hereinabove described are old and well known in the art, and per se, perform no part of my present invention.

15 A nozzle 28 having a wide flat mouth as indicated in dotted lines 30 in Fig. 2, is mounted adjacent each set of terminals 20. Nozzle 28 is preferably of insulating material so as not to impair the effectiveness with 20 which the parts inside container 10 are insulated. Any suitable conduit means 32 is provided to deliver fluid from a tank 34 or other suitable source of fluid under pressure. A suitable valve 36 controlled by 25 lever 38 is normally held in closed position by a spring 40. It may be opened to deliver fluid from tank 34 through nozzle 28 by the action of a solenoid diagrammatically indicated as a winding 42 having a coil 44.

30 Switches of this type are ordinarily designed to open very quickly, i. e., in a small fraction of a second. It will be obvious, that the time required for solenoid 42 to open the valve, is merely a question of design 35 involving the power of the solenoid and the inertia of the moving parts. I have indicated power mains 46 and 48 for operating the solenoid, the circuit being completed by a relay 50 actuated by the usual current 40 transformer in the main power line. It will be obvious that relay 50 may be the same relay closing the circuit for operating the oil switch itself, in which case fluid from tank 34 will always be injected whenever the 45 switch operates, in a predetermined time relationship, depending on the speed of operation of the fluid delivery means, and the speed of the switch itself.

Alternatively, relay 50 might be independent of the control means for the main switch, and might be set to operate only at a slightly higher value of constant current flow than that required to open the switch itself; but on heavy surges of current to operate more 55 quickly than the control means for the switch itself. With such a design, a slight permanent excess of current would open the main switch without utilizing any fluid from tank 34, whereas a heavy surge of current, liable to cause severe arcing in the switch, would result in the delivery of fluid from tank 34 even before the switch contacts separated.

The fluids I at present contemplate using, 60 are oil in the switch itself, and a suitable

arc-extinguishing fluid in tank 34, such as carbon tetrachloride, or the liquid disclosed in U. S. Patent 1,319,907, granted October 28, 1919, to myself and Nicholas J. Conrad. It will, however, be obvious that in its 70 broader aspects, my invention is not limited to the use of any particular fluid or fluids.

Referring now to Figures 3 and 4, I have illustrated, in connection with the same switch shown in Figures 1 and 2, small cartridges or containers 52 and 54 removably fastened in place as by clip 56, and immersed in the contents of the main bath. Each cartridge is provided with a destructible and renewable window or partition 58 80 and 60 respectively, so positioned that if the arcing becomes at all serious, the heat thereof will rupture and destroy the window and release the contents of the cartridge to flow down and extinguish the arc. In the case of 85 oil and a chlorinated hydrocarbon, the flow will be down, as the specific gravity of the extinguishing fluid will be from two to four times that of the oil, depending on the particular oil and extinguishing fluid 90 selected.

Window 58 is arranged horizontal, close to the base of one set of contacts 20 and window 60 is arranged in a vertical plane. It will be apparent that a large number of 95 different positions may be provided.

Switches of this type are usually inspected, and, if necessary, repaired or partially replaced, each time they open. After such a switch as shown in Figure 4 has 100 opened, it will only be necessary for the inspector to throw out the old oil, which he would usually do in any event; and put new cartridges in place when reassembling the switch. The presence of the arc-extinguishing liquid in the bath, does not in any way interfere with temporarily closing the switch after it has once opened, until it is possible to send an inspector to put it in condition for further continuous service. 110

Referring now to Figures 5 and 6, I have illustrated one terminal of another well known type of oil switch. In this construction and imperforate shell 62 contains the main bath, and under normal conditions also 115 carries the current. When an overload occurs, an ordinary contact switch (not shown) opens the circuit through the shell, forcing current to flow thereafter through the central rod 64, from socket 66 to cross-piece 68. 120 Of course, a very small fraction of a second after the ordinary disconnecting switch has opened, cross-bar 68 is forcibly raised, lifting rod 64 out of its socket to finally interrupt the flow of current. 125

In applying the principles of my invention to this type of switch, I preferably provide a unitary holding frame, comprising three uprights 70, preferably of wood, supporting an insulating annulus 72 by means 130

of pins 74, and at their upper ends braced and united by another annulus 76 resting on shoulder 78 formed in the uprights, and surrounded by sleeve 80 covered with a third 5 annulus 82 held in place by pins 84.

Insulator 86 is mounted on a cover plate 88 threaded into shell 62, and preferably clamped against withdrawal by expanding a portion of the thread by means of wedge 10 90. The receptacles, or cartridges 92 are preferably three in number, and are spaced uniformly about the axis of rod 64, each cartridge having an inwardly facing window 94 near its lower end. If the arc 15 drawn in opening the switch follows the end of rod 64 above annulus 72, windows 94 will immediately be destroyed, and the arc-extinguishing fluid in all the cartridges will be simultaneously poured inward 20 directly into the arc.

After the switch has once opened, the inspector can relieve wedge 90 and remove shell 62. The entire supporting framework for the cartridges, can now be simply lifted 25 out, and put back in place with new cartridges, or, in case the frame itself has been too much damaged by the arc, a new frame can be supplied. The entire attachment necessitates no change in the structure of the 30 switch, and can be readily applied to switches now in use.

Referring now to Figure 7, it will be seen that I may curve window 94 outwardly almost into contact with rod 64, and provide 35 the rod with a horn 96 positioned in alignment with each window. When this construction is employed, horn 96 will shatter window 94 before the arc reaches the window, and further movement of the rod will 40 draw the end of the arc directly through the arc-extinguishing fluid liberated by the destruction of the windows.

Without further elaboration, the foregoing will so fully explain the gist of my invention, that others may, by applying current 45 knowledge, readily adapt the same for use under various conditions of service, without eliminating certain features which may properly be said to constitute the essential 50 items of novelty involved, which items are intended to be defined and secured to me by the following claims.

I claim:—

1. In an oil switch the method of interrupting the electric arc which is formed upon separation of the contact, which comprises displacing the oil in contact with the arc by a non-inflammable arc-extinguishing liquid.

2. The method of extinguishing an arc in a body of oil which comprises displacing a part of the oil by another liquid of greater arc-extinguishing capacity.

3. In an oil switch having its contacts submerged in an oil bath, the method of inter-

rupting the flow of current which comprises separating the contacts, drawing an arc in the oil, and by the heat of said arc releasing a body of non-combustible liquid of arc-extinguishing characteristics into contact with the arc. 70

4. In an oil switch having its contacts submerged in an oil bath, the method of interrupting the flow of current which comprises separating the contact, drawing an arc in 75 the oil, and upon the separation of the contacts displacing the oil in contact with the arc by a non-combustible arc extinguishing liquid.

5. In an oil switch, a tank for oil, a stationary contact and a cooperating movable contact, said contact being submerged in the oil in said tank, means for moving the movable contact out of engagement with the stationary contact, a non-inflammable 80 liquid and means effective upon the separation of the contacts for displacing the oil about the contact by the non-inflammable 85 liquid.

6. In combination, a body of insulating 90 liquid, contacts separably engaged in said liquid, and means for introducing a liquid of different character into said body of liquid, said means being effective responsive to the separation of the contacts. 95

7. In combination a tank, oil in the tank, circuit interrupting means submerged in the oil, and means for introducing a non-inflammable liquid into the oil adjacent the circuit interrupting means. 100

8. In combination, two separate bodies of liquid, means for opening a circuit at a point in one liquid body, and means operated only when said opening means also operates, to liberate the other liquid. 105

9. In combination with the bath and circuit interrupting means of an oil switch, a receptacle in said bath above the point at which the arc is formed, an arc-extinguishing medium in said receptacle of higher 110 specific gravity than the bath, a destructible partition forming part of said receptacle, and means for destroying said partition when the switch opens.

10. In combination with the bath and circuit interrupting means of an oil switch, a receptacle in said bath, an arc-extinguishing medium in said receptacle, and a renewable destructible partition forming part 115 of said receptacle and positioned to be destroyed by the arc when the switch opens. 120

11. In combination with the bath and circuit interrupting means of an oil switch, a receptacle in said bath, an arc-extinguishing medium in said receptacle, a destructible partition forming part of said receptacle and positioned to be destroyed by the arc when the switch opens, and mechanical means for rupturing said partition before the arc reaches it. 125 130

12. In combination with the bath and circuit interrupting means of an oil switch, a receptacle containing a non-inflammable arc-extinguishing liquid for extinguishing the arc formed at the circuit interrupting means, and a support for removably mounting said receptacle in said bath.
13. In combination with the bath and circuit interrupting means of an oil switch, a supporting frame work removably mounted in said bath, and a receptacle containing a non-inflammable arc-extinguishing liquid in said bath supported on and removable with said frame work.
14. In an oil switch employing separable contacts and an oil bath surrounding said contacts, the method of interrupting an arc between said contacts which comprises injecting an inert arc-extinguishing liquid into the bath when the switch opens.
15. In an oil switch employing separable contacts and an oil bath surrounding said contacts, the method of interrupting an arc between said contacts which comprises injecting an arc-extinguishing liquid into the bath to form a temporary bath which will evolve a non-inflammable vapor.
16. In an oil switch having a pair of contacts movable with respect to each other to open an electric circuit, the manner of preventing damage to the switch which comprises normally submerging the contacts in a bath of insulating oil when the contacts are closed and replacing said oil bath in part by a bath of a non-inflammable arc-extinguishing liquid when the contacts are moved to open position.
17. In an oil switch employing separable contacts and an oil bath surrounding said contacts, the method of extinguishing an arc between said contacts which comprises moving a body of arc-extinguishing liquid other than the oil of the bath across the path of the arc as the contacts separate.
18. In combination with the bath and circuit interrupting means of an oil switch, a receptacle in said bath containing a non-inflammable arc-extinguishing liquid, and a renewable destructible partition forming part of said receptacle and positioned so as to be destroyed by the arc when the switch is opened to permit the liquid to flow out of said receptacle and into the path of the arc.
19. In an oil switch having its contacts submerged in an oil bath, the method of interrupting the flow of current which comprises separating the contacts, drawing an arc in the oil, and by the heat of said arc releasing a body of non-inflammable arc-extinguishing liquid having a specific gravity higher than that of the oil bath from a point above the arc, so as to permit it to flow into contact with the arc.
20. In an electric switch, two receptacles containing insulating liquid having different insulating properties, means for drawing an arc in the liquid in one of the receptacles, and means for pouring the liquid from the other receptacle into the arc to quench the same.
21. The method of breaking an electric circuit which consists in drawing an arc in an insulating liquid and in quenching the arc by another insulating liquid having higher insulating properties than the first liquid.
22. The method of breaking an electric circuit which consists in drawing an arc in an insulating liquid and in quenching the arc by displacing the liquid adjacent the arc by an insulating liquid having a low boiling point which, upon vaporizing, cools the arc and temporarily produces a region of high pressure adjacent the arc.
23. In combination, a tank, a body of oil in the tank, circuit interrupting means submerged in the oil, a receptacle mounted within the tank, said receptacle containing a body of non-inflammable arc extinguishing liquid of different insulating characteristics and greater arc extinguishing properties than the oil, and means for injecting said non-inflammable arc extinguishing liquid into the tank and adjacent the circuit interrupting means.

In witness whereof, I hereunto subscribe my name this 7 day of October, 1922.

EDMUND O. SCHWEITZER
